BASIN FOR SOFTENING OR COOKING IN WATER OR OTHER LIQUID STOCKS PREPARATORY
TO THE MANUFACTURE OF VENEER, MECHANICAL PULP, OR THE LIKE THEREOF
Filed June 1, 1925

FIG. 1.

FIG. 2.

Inventor,
Axel Emanuel Holmberg,
By Henry Orth Jr. atty.

UNITED STATES PATENT OFFICE.

AXEL EMANUEL HOLMBERG, OF LJUSNE, SWEDEN, ASSIGNOR TO LJUSNE-WOXNA AKTIEBOLAG, OF LJUSNE, SWEDEN, A CORPORATION OF SWEDEN.

BASIN FOR SOFTENING OR COOKING IN WATER OR OTHER LIQUID STOCKS PREPARATORY TO THE MANUFACTURE OF VENEER, MECHANICAL PULP, OR THE LIKE THEREOF.

Application filed June 1, 1925. Serial No. 34,093.

To all whom it may concern:

Be it known that I, AXEL EMANUEL HOLMBERG, a citizen of the Kingdom of Sweden, residing at Ljusne, Sweden, have 5 invented a new and useful improved basin for softening or cooking in water or other liquid stocks preparatory to the manufacture of veneer, mechanical pulp, or the like thereof, of which the following is a specification.

10 The present invention relates to a basin for softening or cooking in water or other liquid stocks preparatory to the manufacture of veneer, mechanical pulp or the like thereof.

15 In basins heretofore used for such purpose no means are provided for securing a uniform softening of the stocks or a uniform dissolution of the incrusted lignin or resin substances surrounding the fibres, i. e. the 20 time during which a stock passes through the liquid in the basin cannot be determined. The object of the present invention is to remove this disadvantage.

The invention consists in the combination 25 of a basin having an approximately semi-cylindrical bottom surface and a freely rotatable wing or shovel wheel journaled in said basin, the shaft of said wheel coinciding substantially with the axis of the semi-cylindrical bottom surface of the basin and the wings or shovels of said wheel being of 30 such radial extension as to prevent the stocks from passing between the bottom surface of the basin and the free ends of the wings 35 or shovels. All stocks supplied to the basin at one side thereof are parallel to the shaft of the wing wheel and are compelled to pass through the basin during a time which is determined by the speed of rotation of the 40 wing wheel which speed in its order is dependent on the quantity of stocks supplied in a unit of time to the basin.

In the accompanying drawing Figs. 1 and 2 show two cross sections at right angles to each other of a basin constructed in accordance with the present invention.

Referring to the drawing, 1 indicates the semi-cylindrical bottom surface of the basin and 2 the plane side walls thereof. In bearings 3 is rotatably journaled a shaft 4 which coincides with the axis of the semi-cylindrical bottom surface 1 and supports 50 a wing wheel. In the construction form

shown this wheel consists of two naves 5 rigidly secured to the said shaft and of a 55 number of arms 6 secured to the said naves. The edge 7 of the basin at which the stocks are supplied lies at a somewhat higher level than the shaft of the wing wheel, while the edge 8 of the basin at which the stocks leave the basin lies at a somewhat lower level than the said shaft. The liquid level of the basin is indicated by 9. The basin may in the usual manner be provided with inlet and outlet pipes for the liquid and with drawing 60 off devices for the wastes that may accumulate on the bottom of the basin. In case hot water or liquid (solution) is to be used for the treatment of the stocks, the heating of the liquid may be accomplished by 65 means of well known heating devices for instance steam pipes or the like. The stocks to be treated are transported to the basin for instance on a conveyer 10 and are thereupon rolled down into the basin over the edge 7, 70 where they are caught by a wing of the wing wheel. According as the number of stocks on said wing is increased the wing wheel is turned until the next wing comes into position to catch the stocks supplied to the basin 75 and so on until the basin has been filled with stocks. In the continued supply of stocks to the basin the wing wheel continues its rotation and lifts the stocks first supplied above the liquid level at the discharge edge 8 of the basin where the stocks successively roll down onto a preferably inclined surface 80 11 from which they are removed in any desired manner. It is obvious that the time during which the stocks pass through the basin is dependent of the speed of rotation of the wing wheel which speed depends on the quantity of stocks supplied per unit of 85 time into the basin and thus may be regulated at will.

From the above it will be seen that the invention at the same time as it renders it possible to determine exactly the time during which the stocks pass through the basin has the great advantage that no special means whatsoever are necessary to take the stocks up from the basin.

Having now described my invention what I claim is:

The combination of a basin of the kind set forth having an approximately semi-cylindrical

drical bottom surface and a freely rotatable wing or shovel wheel journalled in said basin the shaft of said wheel substantially coinciding with the axis of the curved bottom surface 5 of the basin, and the radial length of the wings or shovels of said wheel being such as to prevent the stocks from passing between the bottom surface of the basin and

the free ends of the wings of said wheel, substantially as and for the purpose set forth.

In testimony whereof I have hereunto subscribed my name this eleventh day of May, 1925.

AXEL EMANUEL HOLMBERG.
